UNITED STATES PATENT OFFICE.

MAXIMILIAN K. GOLDEN, OF SAN FRANCISCO, CALIFORNIA, ASSIGNOR TO JAMES JEROME,
OF SAN FRANCISCO, CALIFORNIA.

ELECTRICAL VIBRATOR.

No. 928,043.

Specification of Letters Patent.

Patented July 13, 1909.

Application filed January 15, 1908. Serial No. 410,946.

To all whom it may concern:

Be it known that I, MAXIMILIAN K. GOLDEN, a citizen of the United States, residing in the city and county of San Francisco and State of California, have invented new and useful Improvements in Electrical Vibrators, of which the following is a specification.

My invention relates to an electrically actuated vibrating device.

It consists in a combination of parts, and in details of construction which will be more fully explained by reference to the accompanying drawings, in which—

15 Figure 1 is a horizontal section or plan view with the cap removed. Fig. 2 is a vertical section of same.

It is the object of my invention to produce a vibrating device which may be operated, 20 either by direct or alternating current and without the use of sparking device, induction current, or make and break mechanism, such as is usually employed for such devices.

25 The invention is applicable for moving reciprocating parts of any kind which can be so moved, such as the ringing of bells, the actuating of massage or percussion implements, or anything of like character.

30 In the present case I have shown an inclosing shell A which is adapted to contain an electromagnet 2. This electromagnet is mounted upon a yielding or spring arm, or equivalent 3 which is here shown fixed at 35 one side 4 within the casing A, so that by means of this movable arm the magnet, itself, is capable of motion in connection with the arm. The armature of this magnet, shown at 8, is fixed to the side of the case so that

40 when the electromagnet is alternately energized and deenergized, the armature being stationary, the magnet 2 will be attracted to and released and will thus move with its arm 3. In order to regulate the amplitude

45 of the vibrations I have shown a screw 13 which may have a milled head 14 upon the outside, and the interior shank of the screw may be surrounded by a spring 15 which contacts with the arm 3 so that by compressing

50 the spring, the arm may be forced back to increase the distance between the armature and the electromagnet, and correspondingly increase the amplitude of vibration of the magnet. It may be in like manner reduced 55 by decreasing the tension of the spring. This

adjustment may be made by turning the screw in either direction, the screw passing through a nut in the side of the case. The screw-shank carries a polygonal nut 12, the sides of which contact with a spring, or elastic arm 16, fixed to the side of the case in such position that as each side of the nut is brought into contact with the elastic arm, it will be retained and prevented from further turning, and this insures any adjustment 65 which has been made being maintained without danger of the screw being gradually turned by the vibrating action or other means.

In line with the screw 13, and within the 70 coil spring 15, is a short stem 17, one end of which is secured to the elastic arm 3, and the other extends toward the inner end of the screw 13; and it will be seen by this construction that when the spring 15 is compressed, 75 by turning the screw 13 inwardly, the contiguous ends of the two stems may be caused to approach, or be brought together, and when the screw is turned in the opposite direction and withdrawn, the distance between the two will be increased. Thus the amplitude of vibration of the spring 3, caused by the action of the magnet, can be accurately adjusted to any desired degree. It will be seen by this construction that these 80 vibrations and movements of the magnet may be effected by an alternating current, the magnet being properly wound so that the alternate attraction and repulsion of the magnet with relation to its armature, will 85 take place. If the device is to be used with a direct current, an interrupter for the primary current may be employed with a like result.

The great advantage of this construction 95 is that the expensive make and break mechanism, with the necessary induction current and sparking device, are entirely eliminated, and for the purpose of bell ringing in connection with telephones, or in any place 100 where bells are used, it will make a very great saving in the expense of such apparatus. It is also available for massage instruments, in which connection I have shown the device in the present apparatus. In such 105 a device, the case A may be provided with a handle 10, which is preferably made to carry a cable 9, and said cable carries separate insulated wires which are properly connected with the magnet coils, as shown at 11. I 110

have shown an opening 7 in one side of the case A, and an arm 6 fixed to the vibrating arm 3 extends through the case, and carries upon the outer end a massage implement 5 which is here shown as bell-shaped but may be of any other description. In line with the adjusting stem 13, or approximately so, is another arm as at 18 so disposed with relation to the vibrating arm 3 that the latter 10 may act upon this arm 18 to move it longitudinally. Thus an implement attached to the end of the arm 18, would be moved longitudinally with a patting movement instead of transversely as in the case of the implement 5. Either of such connections may be made as previously stated, with bell or other contrivances, and whatever the connection made, the vibrations may be transmitted in this manner.

20 The operation of the device is easily understood. The vibrations of the electromagnet, which is of considerable weight, impart a very positive movement to the connected part which is to be moved thereby; and under rapid vibration the inertia caused by the weight of the parts, will cause a vibration of the exterior casing as well as that of the magnet.

Having thus described my invention, what 30 I claim and desire to secure by Letters Patent is—

1. In an apparatus of the character described, a case, a vibrating arm having one end fixed to the case, the other end free, having connection for a tool or implement, an electromagnet fixed to said vibrating arm

and movable therewith, a stationary armature fixed with relation to the electromagnet, whereby the energizing and deenergizing of said magnet causes it and the tool-carrying arm to be oscillated with relation to the armature, means for regulating the vibrations, said means including a stem fixed to, and projecting from, the vibrating arm, a screw stem carried by the case and adjustable in line with the first-named stem, and a spiral spring connecting the vibrating arm and the adjusting screw.

2. In an apparatus of the character described, an arm fixed at one end and free at the other, an electromagnet fixed to said arm, a fixed armature, with relation to which the electromagnet and its arm are capable of vibration, means for transmitting the movement of the arm to a reciprocating implement, a stem projecting from the arm parallel with the line of vibration, a screw stem adjustable in line with the first-named stem, a spring uniting the two, a polygonal nut or part fixed to, and turnable with, the screw, and an elastic plate contacting with said part yieldable to allow the screw and part to be turned, and contacting against the flat surfaces intermediate of the angles, to lock the screw in its suggested position.

In testimony whereof I have hereunto set my hand in presence of two subscribing witnesses.

MAXIMILIAN K. GOLDEN.
